BICYCLE LUGGAGE CARRIER

Arthur R. Westermann, 2328 E. Osborn Road,
Phoenix, Ariz. 85016

Filed May 25, 1973, Ser. No. 364,040

Term of patent 14 years

Int. Cl. D12—11

U.S. Cl. D12—158

FIG. 1 is a perspective view of a bicycle luggage carrier showing my new design;

FIG. 2 is a perspective view thereof showing the side opposite to that shown in FIG. 1, with the securing cord omitted therefrom; and

FIG. 3 is a developmental plan view thereof to a reduced scale with the securing cord omitted therefrom.

I claim:

The ornamental design for a bicycle luggage carrier, as shown and described.
